UNITED STATES PATENT OFFICE.

CARLOS A. SCHMIDT, OF OAKLAND, CALIFORNIA.

DESIGN FOR A VEHICLE BUMPER.

Application filed May 31, 1927. Serial No. 22,225. Term of patent 14 years.

To all whom it may concern:

Be it known that I, CARLOS A. SCHMIDT, a citizen of the Republic of Chile, South America, and a resident of Oakland, in the county of Alameda and State of California, have invented a new, original, and ornamental Design for Vehicle Bumpers, of which the following is a specification, refer-

ence being had to the accompanying drawing, forming part thereof.

The figure is a front perspective of a vehicle bumper embodying my new design.

I claim:

The ornamental design for a vehicle bumper, substantially as shown.

CARLOS A. SCHMIDT.
